UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

DOOR OPERATING MECHANISM

Application filed January 29, 1931. Serial No. 511,952.

This invention relates in general to apparatus and circuits by means of which the power operated doors of vehicles can be opened and closed.

5 One of the objects of this invention is the provision of apparatus and control circuits by means of which the doors on a side of a car or cars may be controlled from several points on the car or cars and which mechanism requires in some of its operations the insertions of a key by an authorized person before the apparatus can be operated.

A further object of this invention is the provision of a switch mechanism for use in 15 these circuits which is partially controlled by means of a key.

A still further object of this invention is the provision of a switch which is operated manually to effect closing of the doors, which 20 switch when released snaps back to a normal position in which it is locked and from which it cannot be moved for control of the circuits until the proper key is inserted.

These and many other objects, as will appear from the following disclosure, are secured by means of this invention.

This invention resides substantially in the combination, construction, arrangement, relative location of parts, and circuital connections, all as will be described in greater detail hereinafter.

Referring to the drawings—

Figure 1 is a front outside elevational view of the switch of this invention;

35 Fig. 2 is a cross-sectional view on the line 2—2 of Fig. 1;

Fig. 3 is an enlarged front elevational view of the switch with the cover, a portion thereof being broken away;

40 Fig. 4 is an enlarged outside detail elevational view;

Fig. 5 is a developed view of the contact on the drum of the switch;

Fig. 6 is a diagrammatic view of the connections of the apparatus employing this switch as applied to a single car;

Figs. 7, 8 and 9 are diagrammatic illustrations of the switch positions of a form of this switch as applied to a single car;

45 Figs. 10 and 10^a taken together provide a

diagrammatic illustration of the circuit connections of this invention as applied to two cars; and

Figs. 11, 12 and 13 are diagrammatic illustrations of the positions of the drum switches employed for grouping the circuits of this invention for multiple unit control.

This invention will be described in detail in connection with the drawings from which its nature and operation will best be understood. As shown in Figs. 1 and 2 the switch comprises a base-plate 11 over which fits a cover 1 having a raised central portion 2 to provide a housing for the parts. This raised portion 2 is provided with a projecting hood 3 in which are located buttons 4 and 5 for operating switches within the casing. At 6 is a removable plate which is provided with a keyhole 7. This plate forms part of the cover portion 2. Screws 8 are provided for securing the cover 1 to the base-plate 11. Screws 9 are provided for mounting the complete structure on any suitable support, 10 represents the handle by means of which the switch mechanism is operated in part, or in a counter-clockwise direction.

Referring to Fig. 2 it is noted that the raised portion 2 of the cover is provided with internally projecting bosses 10' in which the push buttons slide. The boss is so formed and the push buttons are so formed as to provide recesses within which springs 11' are provided for resisting depression of the buttons. Secured to for movement with the buttons are contact strips 12. At 15 is a standard secured to the base-plate on which is secured a block of insulating material 14. Secured to this insulating block in spaced relation are the contacts 13 arranged in alignment with the contact strip 12. The switches controlled by both push buttons 4 and 5 are the same in construction. When either push button is depressed its spring is compressed and the contact strip 12 controlled thereby is moved to bridging position with respect to the fixed contacts 13 to complete circuits connected thereto.

At 16 is a bracket having a transverse bar 17 which is secured to the base-plate by means of screws 17'. The other end of brack-

et 16 is provided with a ring-shaped member 18. Secured to each side of the bracket are blocks of insulating material 19 which have two right angled parallel walls of insulating material 20. Secured on the right hand block 19 (see Fig. 3 in connection with Fig. 2) are three contact fingers 21, 22 and 23. These contact fingers, as well as the corresponding contact fingers 34, 35 and 36, are arranged so as to pivot upon the metal strips 25 secured to the insulating blocks. The spring fingers are held in position by means of pins 24 secured in the metal bars 25 and projecting through the spring fingers. Compression springs encircle these pins and engage the spring fingers to permit their swinging outward about their pivot points under the resilient reaction of the springs.

At 26 is a shaft which is journaled in the base-plate at one end and which is provided at the other end with a disc 33 rotatably supported in the ring 18. Mounted on shaft 26 for rotation therewith is a drum of insulating material 27 upon which is supported a contact plate 28. The shape of the contact plate is shown in Fig. 5 in development, although when applied to the drum it assumes a curved form. Secured to shaft 26 for rotation therewith is a short arm 29 which is mounted so that in its movement it engages with the vertically slidable rod 30. This rod is slidably supported in bearing 31 and a hole in the bar 17. This rod is encircled by a spring 32 which lies against bar 17 and collar 31' which is secured to rod 30. Thus, when arm 29 engages rod 30 and pushes it upwardly, it does so against the reaction of spring 32. At 37 is a stop secured to the base-plate to limit, by its engagement with arm 29, the clockwise rotation of shaft 26 and drum 27.

Disc 33 is generally circular in outline and is rotatively supported within ring 18. As stated above, this disc is secured to the forward end of shaft 26 and performs, as one function, a support therefor. The shaft 26 is square and fits into a square central opening in the disc to effect continued rotation. This disc is also cut away on the lines 39, as shown.

Secured to the disc is a projecting pin 38 which has a function to be described later. Disc 33 is provided for a limited portion on its periphery with a groove 40 which extends completely across its thickness. A complementary, but slightly longer groove 41 is cut in ring 18, which groove does not extend all the way through the thickness of the ring, as is clear from the drawings. Within a suitably shaped hole in disc 33, with the axis of the hole parallel to the sides of the disc, is a pin 42 which projects beyond the edge 39 and is provided with a head 43. Secured to the periphery of ring 18 is a long spring 44 which is provided at its free end with a pin 45 which projects through ring

18 and contacts with the rounded end of pin 42. As is clear from Fig. 3, the pin or lug 45, in the position which spring 44 normally holds it, projects into the path of notch 40 to limit the clockwise rotation of disc 33, shaft 26, and drum 27. However, when pin 42 is moved inwardly it forces lug 45 out of the path of notch 40 so that disc 33, shaft 26 and drum 27 may be given a clockwise rotation. Whether or not the lug is in locking position, disc 33 may be given counter-clockwise rotation.

Referring to Figs. 2 and 4, it will be seen that the circular plate 6 secured to the face of the raised portion 2 of the cover is provided with a semi-circular integral ring portion 50 which holds the plate 6 in spaced relation with the portion 2 of the cover. The central portion of disc 6 projects inwardly, as shown at 53, in conical form. This conical portion is cut away to provide the key-hole 7. The plate 46, which is formed integral with the handle 10, is provided with two arcuate portions 51 and 52 (Fig. 4) which have an external diameter approximately the same as the internal diameter of the opening in the casing projection 2. These arcuate lugs form a centering and rotating surface for the arm 10 and its integral plate 46 so that all of these parts may be revolved. The plate 46 is cut away centrally so that the conical central portion 53 of the outer disc 6 projects therethrough. The lugs 51 and 52 are on a circle indicated by the dotted lines 61 in Fig. 4. The conical portion 53, which projects through plate 46, terminates along the dotted line 60 in Fig. 2. Lug 38 on disc 33 lies between the arcuate lugs 51 and 52 so as to be in their path of movement. Thus when the handle 10 is moved to the right (Fig. 4) the right hand end of lug 52 engages the pin 38 and causes disc 33, drum 27, and arm 29 to rotate in a counter-clockwise direction against the resistance of spring 32.

When a proper key is inserted in keyhole 7 and the key is rotated clockwise the tongue of the key bears against pin 42 and thus forces lock 45 out of the path of disc 33. A further clockwise rotation of the key rotates disc 33, shaft 26, and drum 27 from their normal position until arm 29 (Fig. 2) strikes the stop 37. For purposes of description the position to which drum 27 has been rotated is referred to as the "second position". The key can then be withdrawn without causing any rotation of disc 33. The parts will remain in this second position until returned by application of force to handle 10. When force is applied to handle 10 its integral lock 52 bears against pin 38 and thus causes disc 33, drum 27, and arm 29 to rotate counter-clockwise. When this rotation has proceeded in a counter-clockwise direction to the normal position, pin 45 under the

pressure of spring 44 drops into groove 40 and disc 33 and thus prevents clockwise rotation of disc 33, drum 27, and arm 29 until a proper key has again been used. The said counter-clockwise rotation can be carried further by the application of force to handle 10 though such further rotation is yieldingly opposed by rod 30 and spring 32 bearing on arm 29. The full counter-clockwise movement of handle 10, disc 33, and drum 27 is reached when arm 29 is stopped by striking bearing 31 which is integral with the base 11. This position of drum 27 and the handle 10 is hereinafter referred to as the "third position" of the switch.

15 The pressure of spring 32 on rod 30 and against arm 29 is such as to rotate in a clockwise direction arm 29, drum 27, disc 33, and handle 10 when pressure is released from handle 10 until this rotation is stopped by disc 33 striking pin 45. The travel of rod 30 and spring 32 is limited by collar 31' striking bearing 31 but sufficient travel is provided so that disc 33 is held against pin 45 thus keeping drum 27 in its normal position until pin 45 is forced out of the path of disc 33 as above described or until pressure is applied to handle 10 in a counter-clockwise direction. It is apparent that handle 10 may be used to rotate disc 33 and drum 27 from the normal position to the "third position" without the use of a key.

A feature of the construction as herein described is that as bracket 16, insulating blocks 19, contact fingers 21, 22, 23, 34, 35 and 36, shaft 26, drum 27, the contact piece on drum 27 and the disc 33 as well as block 14 and contacts 13 are carried by base 11, the cover 1 may be removed from the switch without distorting the connections to the contacts, the alignment of the shaft 26 and disc 33 in the supporting bearings on the base-plate and in ring 18, the alignment of drum 27 with respect to the contact fingers or the positions of the drum 27 as determined by stops 37, 45 and 31.

The removal of the cover carries with it as a unit assembly the push buttons 4 and 5, the escutcheon plate and the operating handle.

The circuits and apparatus used in connection with the above described switch, and circuits for one car have been set forth diagrammatically in Fig. 6. The outline of the vehicle, to which the invention can be applied, is shown at 70. This vehicle is provided in the usual manner with a plurality of doorways, not shown, on each side of the car which doorways have movable doors, likewise not shown. These movable doors are operated by means of motor devices which are shown in the drawings as pneumatic motors 71 and 72. The motor 71 is provided with magnet valves 73 and 74, and motor 72 is provided with magnet valves 75 and 76. Magnet valves 73 and 76 are the

magnet valves which control the closing operations of the motors, and magnet valves 74 and 75 control the opening operations of the motors.

The fluid pressure motors, indicated diagrammatically in the drawings, form no part of this invention but may be of a number of well known constructions. Briefly, they comprise cylinders having two connected pistons movable therein. When the pistons move in one direction fluid pressure is being admitted to one end of the engine and exhausted from the other, and when moving in the opposite direction, fluid pressure is admitted to the previously exhausted cylinder and the other cylinder is exhausting to the atmosphere.

The magnet valves are, likewise, known in many forms and are of such construction that when energized they supply fluid pressure to the cylinder to which they are connected, and when deenergized open the cylinder to which they are connected to atmosphere. Thus magnet valve 73 when energized supplies fluid pressure to the left hand end of engine 71, while magnet valve 74, which is not energized, permits exhaust of fluid pressure from the right hand end of this motor. One terminal of each of the magnet valves is grounded as shown. The other terminal of each of magnet valves 73 and 74 is connected to wires 81 and 79, respectively. The other ends of these wires are connected to contacts of a suitable switch, such as push button switches which have been indicated at 78 and 80. The other terminals of each of these switches are connected together and connected to wire 77 which, in turn, leads to the positive side of the current source. Thus, assuming the door is closed, when push button switch 78 is closed current flows through the winding of the magnet valve 74 energizing it so as to supply fluid pressure to the right hand end of the engine 71 to cause it to open the door. The other end of this engine is open to exhaust through magnet valve 73 which is deenergized. Like operations occur to close the door when push button 80 is closed.

The switch described in Figs. 1 to 5, inclusive is shown at each end of the car. At this point it is noted that the circuits for the doors on one side of the car only are shown and for two motors only. Of course the parts can be duplicated for any number of motors and the parts shown are duplicated complete for the doors on the other side of the car. Thus there will be four of these switches, two on each end of each car. The drum of each switch is indicated diagrammatically at 27 and at 28 is shown the contact plate mounted thereon. This plate is of the shape shown in Fig. 5. 21, 22 and 23, and 35, 36 and 37 are the spring fingers of the switch which are mounted to contact with plate 28 to establish various connections when the drum 27 is ro-

tated. These various connections are indicated in Figs. 7, 8 and 9.

Spring finger 22 of the left hand switch is connected by wire 91 to wire 81. Spring finger 21 of the left hand switch is connected by wire 90 to one of the contacts of push button switch 89 at the other end of the car. The other contact of this switch is connected by wire 88 to wire 83 which runs to the positive side of the current source. Spring finger 23 is connected to spring finger 35 and to wire 82, which likewise connects to the positive side of the current source. Spring finger 37 of the left hand switch is connected by wire 92 to one of the contacts of push button 93. The other contact of this push button is connected by wire 94 to wire 79.

Spring finger 36 is connected by wire 95 to one terminal of push button switch 96. The other terminal of this push button switch is connected by wire 97 and wire 100 to one terminal of magnet valve 75, the other terminal of which is grounded. Wire 97 also connects to one terminal of push button switch 98. The other terminal of this switch is connected by wire 99 to spring finger 37 of the right hand switch. Wire 82 is connected by wire 84 to one terminal of push button switch 85. The other terminal of this switch is connected by wire 86 to spring finger 21 of the right hand switch. Wire 79 is connected by wire 104 to one terminal of push button switch 103. The other terminal of this switch is connected by wire 102 to spring finger 36 of the right hand switch. Wire 83 is connected to spring fingers 35 and 23. Spring finger 22 of the right hand switch is connected by wire 87 to one terminal of magnet valve 76, the other terminal of which is grounded.

It is pointed out that push button switches 93, 96, 98 and 103 are the push button switches corresponding to the buttons 4 and 5 of Figs. 1 and 2. It has already been pointed out how push button switches 78 and 80 may be used to operate the motor 71 which is adjacent the guard's position. In other words, these switches merely provide a convenient auxiliary arrangement whereby the guard may operate the motor of the doors adjacent his position independently of the rest of the system and of all the other motors and doors on the car or on the cars of the unit which he controls.

Push button 85 is provided so that the guard may close the non-adjacent door of his car to his right from a position where he can observe the door. Similarly push button 89 is provided so that the guard may close the non-adjacent door in his car to his left if he be at the right hand end of the car. Where the guard controls the doors of a number of cars to each side of him then, of course, a push button 85 and a push button 89 will be available at his station between or at the ends of

the two cars at the inner ends of the groups which he controls. In this case push button 85 will close all the non-adjacent doors of all the cars of the group to his right and push button 89 will close all the non-adjacent doors of the group to his left. This will appear in more detail in connection with Figs. 10 and 10^a. Thus, when the operator closes push button switch 85 current flows from the positive side of the current source through wires 82, 84, switch 85, wire 86, spring finger 21, contact plate 28, spring finger 22, wire 87, and through the magnet valve to ground. If the door connected to motor 72 is open it can thus be closed from the opposite end of the car. In a similar manner, when switch 89 on the other end of the car is closed, current flows through magnet valve 73 of motor 71 to close the door at the opposite end of the car. These operations with switches 85 and 89 can only be carried out when the drum switch at the opposite end of the car from which the operated switch is situated is in what is known as the normal or locked position. As shown diagrammatically in Fig. 7, the drum 27 is then in the position where contact plate 28 interconnects spring fingers 21 and 22 only. With respect to Fig. 1, for example, the locked position of the drum switch is that position which that switch normally assumes after it has been moved counterclockwise from the second or unlocked position to or past the position where pin 45 drops into notch 40 of disc 33. At this time the switch is locked, as already described, so that disc 33 and drum 28 cannot be moved clockwise from the normal position until the disc 33 is unlocked with the proper key. It can be moved to the right against spring 32 but if pressure is not being applied to it it is in its normally locked position, at which time the closing operations with switches 85 and 89 can be carried out.

When the guard desires to effect opening and closing operations of the doors from his normal position, which is assumed for this discussion to be the left hand end of the car, he inserts a key into the drum switch. It is to be remembered that the other drum switch or drum switches, if there are a number of cars under his control, are in the locked position (Fig. 7). He inserts the key in keyhole 7, and gives it a clockwise rotation. The lug on the key engages the head 43 (Fig. 3) pushing pin 42 in so as to move lock 45 out of the path of disc 33. A further clockwise rotation of the key rotates disc 33, shaft 26, and drum 27 to the second or unlocked position of the drum switch (Fig. 8) in which position spring fingers 35, 36 and 37 are interconnected. He then returns his key to its original position and withdraws it from the switch. The drum remains in operated position. Push button switches 93 and 96 are now in control of the circuits so that all the motors

on that side of the car may be energized to open the doors. By closing push button switch 93 current flows from the positive side of the current source through wire 83 to spring finger 35, through contact plate 28, to contact finger 37. Current then flows through wire 92, switch 93, wire 94, and wire 79 to magnet valve 74. This valve is energized and fluid pressure is supplied to motor 71 to cause the opening of the doors connected thereto. Similarly the closing of push button switch 96 causes current to flow through wire 95, wire 97, wire 100 and magnet valve 75 causing motor 72 to open the non-adjacent door. After the doors have been opened as described, the drum switch may be left in the second position or returned to normal position as desired by the train guard without effecting the closing of the doors.

When it is desired to close the doors the procedure is for the car guard to close the non-adjacent doors first for in so doing he must look along his train at these doors and the adjacent door is left open to facilitate this. The non-adjacent doors are closed from push button 85 as already described. The guard then returns to the handle 10 of the control switch and rotates this counter-clockwise until the arm 29 of this switch and with it shaft 26 and drum 27 are stopped by bearing 31. This is the third or adjacent door closed position of this switch as shown in Fig. 9 so that spring fingers 22 and 23 are interconnected. Current then flows from the positive side of the current source through wire 82 to spring finger 23 to energize contact plate 28. Current then flows through spring finger 22, wire 91, and wire 81, to magnet valve 73. Fluid pressure is then supplied to the other side of the engine so that motor 71 closes the door. In this third position of the drum switch arm 29 is in engagement with rod 30 and has moved it upwardly compressing spring 32. As soon as the adjacent door starts to close the guard may release lever 10 and then lever 10, drum 27, shaft 26, and arm 29 snap back to normal position under the influence of spring 32.

It may be well to point out here that switches 85 and 89 are placed in such a position on the car that the guard in order to reach and operate them will be in a position where he can look down the side of the car and observe whether the doorways are clear. The position of the drum switch is not so important and hence can either be adjacent the push button switches 85 and 89 or at some other point. The main requirement is that the push button switches 85 and 89 which control the closing of the non-adjacent doors be placed so that the guard is in a position to observe the doors along the side of the car. Independent controls as shown by switches 78 and 80 are located in the motor-man's cab so that the motorman may open

and close the door adjacent his position. He may, likewise, close the door at the other end of the car, if it should be open, by operating switch 85. He can open the doors at both ends of the car by unlocking the drum switch and rotating it to the position shown in Fig. 8. He may close the door adjacent his station by rotating the drum switch to the position shown in Fig. 9. Finally, he may close the door at the other end of the car by closing switch 85.

The invention as applied to two cars will now be described in considerable detail in connection with Figs. 10 and 10^a which are to be taken together, and Figs. 7, 8 and 9 and Figs. 11, 12 and 13. The purpose of describing the application of this invention to two or more cars is to illustrate the adaptability thereof employing the principles of multiple unit control as now well known in this art. By suitably arranging the circuits on the cars and providing for the interconnection of these circuits between adjacent cars it is possible to break up these door control circuits employing the principles of this invention to adapt them for use on a train comprising any desired number of units composed of any desired number of cars. To do this additional switches which are disclosed in this instance as drum switches, are provided to interconnect the circuits of the cars. These drum switches have three positions which may be termed the "on", "off" and "through" positions. The normal practice is to have the door guard control the doors of a number of cars to his right and to his left. For example, he may control the doors of two cars to his right and two cars to his left. In this case his control station will be at the adjacent ends of the two innermost cars of the group. At this position the drum switches are in the "on" position as indicated in Fig. 11. The drum switches at the adjacent ends of the two cars to his right and the two cars to his left are in the "through" position as indicated in Fig. 13. Drum switch 123^a (Fig. 10) differs from drum switch 123^b (Figs. 10^a and 13) only in the relative position of the shorter contact.

This is because these switches are at opposite ends of the cars and the shorter contact is shifted as shown to preserve the symmetry. The drum switches at the far end of the second car to his right and the far end of the second car to his left are in the "off" position as indicated in Fig. 12. It is believed that this description is sufficient since the use of such switches for connecting the door control circuits of prior known systems to adapt them for multiple unit control are well known.

Referring now to Figs. 10 and 10^a there are shown the connections for the circuits of this invention for two cars 70^a and 70^b. It will be assumed that the cars are moving

from left to right and that the guard stationed is at the upper left hand corner of car 70^a. He will thus control from that position all the doors on the left hand side of the train with respect to his direction of motion, which cars will be to his right. If desired a similar group will be under his control and extend to his left. It is hardly necessary to point out that he may control the doors of any number of cars of a group to his right and if desired of a similar group to his left. Car 70^a is provided with the fluid pressure actuated engines 71^a and 72^a. It is, of course, understood that the invention is not limited to the number of engines which may be controlled since as many engines for as many doors as desired may be added into the circuits in an obvious manner. Engine 71^a is provided with the opening and closing electromagnet valves 74^a and 73^a and engine 72^a is provided with the opening and closing magnet valves 75^a and 76^a. These valves when energized and de-energized control the admission and exhaust of fluid pressure to the engines in the manner already described in the connection with these devices in Fig. 6. One terminal of the winding of each of the solenoids of these valves is grounded as indicated. The other terminal of the winding of valve 73^a is connected by wire 81^a to two fixed spaced contacts. In a similar manner the other terminal of the solenoid winding of magnet valve 74^a is connected by wire 79^a to two fixed spaced contacts. One of the fixed contacts of each of these groups is connected to a wire 77^a which leads to the positive side of the current source. The other fixed contact of push button switch 80^a is connected by a wire 120 to spring finger 22^a. At each end of the car is provided a drum switch of the type already described and denoted by 27^a and 27^b respectively. Of course there are supplied similar switches for the doors on the other side of the car which doors have not been shown for the sake of simplicity. The other terminal of push button switch 78^a is connected by wire 137 to a fixed terminal of push button switch 93^a. Push button switches 78^a and 80^a are the motorman's auxiliary switches which have already been described and are mounted in his cab so that he may open and close the door adjacent to his station. These switches differ from the corresponding switches 78 and 80 of the system of Fig. 6 in that they have both front and back contacts. In their normal position they interconnect the front contacts and when they are moved to interconnect the back contacts they close circuits to operate the motor to open and close the door. Wire 137 is connected by wire 136 to spring finger 135 of a second drum switch 123. Spring finger 23^a is connected to the positive side of the current source by wire 82^a and by wire 84^a to one of the contacts of push button switch 85^a. The other contact of this switch

is connected by wire 121 to spring finger 122. Spring finger 21^a is connected to wire 124 which extends through the car to the other end. Spring finger 35^a is connected to wire 82^a. Spring finger 37^a is connected by wire 139 to the other contact of push button switch 93^a. Spring finger 36^a is connected by wire 138 to one contact of push button switch 96^a. The other contact of this switch is connected to wire 134 which extends through the car to the other end thereof. Wire 134 is connected by wire 133 to spring finger 132. Spring fingers 129 and 127 are connected by wires 130 and 128 respectively, to a coupling plug 137 to effect an interconnection between the circuits, as will be described later, with the next car through a similar plug. Wire 124 is connected by wire 125 to spring finger 126. It should be noted that drum switches 123, 123^a, 123^b, and 123^c are all similar, being provided with a single rotatable drum and six fixed spring fingers arranged in groups of three. These switches have three positions as indicated in Figs. 11, 12 and 13. It is not necessary to describe the construction of these switches since they are well known in many forms in the prior art.

At the other end of car 70^a is equipment similar to that already described. It will be referred to in detail, however, since the parts have been given different reference numerals in order to aid in tracing circuits. The engrounded terminal of the winding of magnet valve 76^a is connected by wire 120^a to spring finger 22^b. Likewise the engrounded terminal of magnet winding 75^a is connected by wire 136^a to spring finger 135^a. Wire 136^a is connected by wire 137^a to one terminal of push button switch 98^a. Wire 134 is connected to one terminal of push button switch 103^a and by wire 140 to spring finger 132^a. Wire 124 is connected by wire 125^a to spring finger 126^a. Spring finger 122^a is connected by wire 121^a to one terminal of push button switch 89^a. The other terminal of this switch is connected by wire 88^a to the wire 83^a connected to the positive side of the current source and to spring fingers 35^b and 23^b. Spring finger 37^b is connected by wire 99^a to the other terminal of push button switch 98^a. Spring finger 36^b is connected by wire 102^a to the other terminal of push button switch 103^a. Spring fingers 129^a and 127^a are connected by wires 130^a and 128^a to the plug 137^a.

Similar connections are set up in Fig. 10^a for car 70^b and similar parts have been given the same reference numeral with a different exponent to aid in tracing the circuits. It is not believed necessary, however, to describe the various connections in Fig. 10^a since they are exactly the same as those in Fig. 10. The control switches 27^a and 27^b, 27^c and 27^d are exactly the same and are in the position, that is, the normal or locked position at which

time the doors are assumed to be closed to provide a starting point from which to describe the circuits. The interconnecting plugs 137^a and 137^b are joined so that the 5 circuits on the two cars are ready for the proper interconnection by the appropriate setting of switches 123, 123^a, 123^b, and 123^c. Thus switch 123 is shown in the "on" position being adjacent the guard station. Switches 10 123^a and 123^b are shown in the "through" position to continue the circuits through from car 70^a to 70^b so that the one guard may control all the doors on one side of both cars. Switch 123^c is in the "off" position thus terminating the guard's control at the right hand end of car 70^b. Of course all the interconnecting plugs 137 for the whole train are connected and the circuits of the train may be divided up by switches 123 to provide any 15 desired number of units composed of any desired number of cars with regard to door control.

To open the doors the guard inserts his key into keyhole 70 of switch 27^a at his station 20 and rotates the drum in a clockwise direction as already described to move it to the second or unlocked position when connections will be established as indicated in Fig. 8. This puts current from wire 82^a on all of spring 25 fingers 35^a, 36^a and 37^a. He then closes push button switch 96^a causing current to flow from spring finger 36^a through wire 138, switch 96^a, wire 134, wire 140, spring finger 132^a, contact 141^a, spring finger 135^a, wire 136^a and through 30 the winding of magnet valve 75^a to ground. This valve being energized admits fluid pressure to engine 72^a to cause it to open the door connected thereto. Spring finger 129^a also being connected to contact 141^a delivers current through wire 130^a, connectors 137^a, and 40 137^b to wire 130^b and spring finger 129^b. Current then flows on through contact 141^b to spring finger 135^b, wire 136^b normally closed push button 78^b, wire 79^b and through 45 the winding of magnet valve 74^b to ground. Thus motor 71^b opens its door. Current also flows from spring finger 132^b to wire 133^a, wire 134^b, wire 140^a, spring finger 132^c, contact 141^c, spring finger 135^c, and wire 136^c 50 to the winding of magnet valve 75^b to ground. This causes motor 72^b to open its door. Thus by the closing of push button switch 96^a with control switch 27^a in unlocked position the guard from his station may open all the non- 55 adjacent doors under his control. The closure of push button switch 93^a causes current to flow from spring finger 37^a through wire 139, switch 93^a, wire 137, normally closed switch 78^a, wire 19^a and through the winding 60 of magnet valve 74^a to ground. Thus member 74^a opens the door adjacent the guard. It is to be remembered that drum 27^a has been moved to the unlocked position in which position it remains even though the key is removed. The other drums 27^b, 27^c, and 27^d 65

are in the locked position as indicated in the drawings and in Fig. 7.

After the doors have been opened as described the drum switch may be left in its second position to which it has been actuated 70 to effect the opening of the non-adjacent doors or returned to normal locked position as desired without effecting the closing of any of the doors. When he desires to close the doors he must move over to switch 85^a 75 and close it. Current then flows from wire 82^a through wire 84^a, push button switch 85^a, wire 121, spring finger 122, contact 141, spring finger 126, wire 125, wire 124, spring finger 21^b, contact 28^b, spring finger 22^b, 80 wire 120^a and through the winding of magnet valve 76^a to ground. Motor 72^a then closes the door connected thereto. Current also flows from wire 124 through wire 125^a, 85 spring finger 126^a, contact 141^a, spring finger 127^a, wire 128^a, plug connectors 137^a and 137^b, wire 128^b, spring finger 127^b, contact 141^b, spring finger 126^b, wire 125^b, wire 124^b, 90 spring finger 21^c, contact 28^c, spring finger 22^c, wire 120^b, normally closed push button 80^b, wire 81^b and through the winding of magnet valve 73^b to ground. Motor 71^b then closes its door. Current also flows through 95 wire 124 to spring finger 21^d, contact 28^d, spring finger 22^d and wire 120^c to the winding in magnet valve 76^b and ground. Engine 72 then closes its door. This the closing of switch 85^a causes the motors of the non-adjacent doors to operate them to closed position. 100

The guard closes his adjacent door by rotating handle 10 of his switch in a counter-clockwise direction as already described so that drum 27^a assumes its third position, that is, adjacent door closed position, as shown 105 in Fig. 9. Current then flows from wire 82^a to spring finger 23^a, contact 28^a, spring finger 22^a, wire 120, normally closed switch 80^a, wire 81^a and through the winding of magnet valve 73^a to ground. Motor 71^a 110 then moves the adjacent door connected thereto to closed position. The release of handle 10 permits spring 32 to move drum 27^a to normal locked position as shown in Fig. 7. The doors are now all closed. It will be remembered that switches 78^a and 80^a and the corresponding switches on each of the cars are provided so that any car may constitute the head-end of the train with the switches 115 in the motorman's cab so that he can without affecting any of the other doors on the train open and close the door adjacent to his cabin when he desires. 120

From the above description it will be seen 125 that first the door opening function is locked against its use by unauthorized persons; second, that the guard may unlock the door control drum switch adjacent his station and then withdraw his key without causing the doors to open. He may then open the non-

adjacent doors by closing his switch 96^a and the adjacent door by closing his switch 93^a; third, he can only open his doors after the control switch has been unlocked; fourth, he may open his adjacent door without opening the non-adjacent doors or, vice versa, depending upon which of the switches 96^a and 93^a he closes; fifth, he may open all the doors under his control to his right and/or left by the operation of both of these switches; sixth, that after his non-adjacent doors have been opened he must proceed to switch 85^a which is so located that he can observe these doors while operating the switch in order to close them. It is pointed out that if he is controlling the doors of a unit to his left he will also have to close switch 89 for this purpose. Seventh, his adjacent door cannot be closed until his drum switch has been turned to locked position; eighth, when he releases the handle 10 after closing his adjacent door it returns to a normal position automatically which is the locked position. Thus he is insured that his control switch will be in locked position after he closes his adjacent door. Ninth, the handle 10 may be moved from normal locked position to the third position to close the adjacent door without the use of a key.

From the above it will be apparent that when his drum switch is in any position other than the second or unlocked position the control switch for the adjacent door is electrically disconnected from the control switch for the non-adjacent door so that should anyone operate both of these switches at some control location remote from and other than that of the guard while the latter is operating one of his control switches the operation of both switches remote from the guard will not permit a back-up circuit to open doors which the guard does not wish opened.

From the above description it will be apparent that this invention resides in certain principles of construction and operation which may be embodied in other physical forms and I do not, therefore, desire to be strictly limited to this disclosure given for purposes of illustrating these principles, but rather to the scope of the appended claims.

What I seek to secure by United States Letters Patent is:

1. In a system of the type described, the combination comprising a plurality of motive devices, electro-magnetic means for controlling the operation of said motive devices, a key released door switch releasable by a key for movement in one direction, a manual switch, and circuits including said electro-magnetic means, door control switch and manual switch, whereby the motive devices can be operated in one direction upon key release of the door control switch and operation of the manual switch and in the

opposite direction upon movement of the control switch in the opposite direction.

2. In a door control system of the type described, the combination comprising at least two motive devices, magnetic means for controlling the operation of the motive devices, a key released control switch, manual switches, and circuits including the control switch and the manual switches, said control switch operable upon key release to one position to partially complete circuits to the motive devices for operation in door opening direction and freely operable to another position to cause one of the motive devices to operate in the door closing direction, said manual switches completing circuits to cause the motive devices to operate in door opening direction.

3. In a system of the type described, the combination comprising at least two motive devices, magnetic means for controlling the operation of the motive devices, two key releasable control switches, three manual switches, and circuits including said magnetic means, said control switches and said manual switches, the operation of either of said control switches upon key release to one position partially completing the circuits to said magnetic means, one of said manual switches being operable to finally energize the magnetic means to cause one of the motive devices to operate in one direction, another of said manual switches being operable to finally energize the magnetic means to cause the other motive device to operate in one direction, the third manual switch being operable to energize the magnetic means to cause one of the motive devices to operate in the opposite direction and either of said control switches being freely operable to another position to energize said magnetic means to move the other of the motive devices in the opposite direction.

4. In a system of the type described for operating the doors of a vehicle, the combination comprising a motive device at each end of the vehicle for operating the doors thereof, magnetic means for controlling the operation of the motive devices, circuits for said magnetic means including a key releasable control switch and manual switches, said control switch being operable upon key release to one position to partially complete the circuits to the magnetic means, certain of said manual switches being operable to complete the circuits to the magnetic means to cause the motive devices to operate the doors to open position, another of said manual switches being operable to complete circuits to said magnetic means to cause one of the motive devices to operate the associated doors to closed position, and said control switch being movable to another position to energize the magnetic means to cause the

other of the motive devices to operate the associated doors to closed position.

5. In a system of the type described for operating the doors of vehicles, the combination comprising two motive devices for operating the vehicle doors, magnetic means for controlling the operation of the motive devices, and circuits for said magnetic means including two key controlled switches, one 10 for each end of the car, and two manual switches, the operation of either of the key controlled switches upon release by a key to one position partially completing circuits to said magnetic means to cause the motive 15 devices to open the doors when the manual switches are closed, and said key controlled switches being operable to another position to energize the magnetic means to cause the motive devices to close the door adjacent the 20 particular key controlled switch which has been actuated.

6. In a system of the type described for operating the doors of vehicles, the combination comprising two motive devices, magnetic 25 means for controlling the operation of the motive devices, circuits for said magnetic means including a control switch at one end of the car, two manual switches at the same end of the car and a third manual switch, 30 said control switch being operable to two positions from a normal position, one to partially complete circuits to the magnetic means, to cause both motive devices to open the door, when the manual switches at that end of the 35 car are closed, and to the other position to cause one of the motive devices to close one of the doors, said third manual switch being actuatable to cause the other motive device to close its doors when the control switch is in 40 normal position.

7. In a system of the type described for operating the doors of vehicles, the combination comprising two motive devices, magnetic means for controlling the operation of the motive devices in either direction, circuits for said magnetic means including a control switch and manual switches, said control switch being operable to one position to partially close circuits to cause the motive devices 45 to open the doors when the manual switches are closed, and movable to another position to cause one of the motive devices to close the doors connected thereto, another of said manual switches being actuatable when said control switch is in a third position to cause the other motive device to close its doors.

8. In a system of the type described for operating the doors of vehicles, the combination comprising two motive devices for operating the doors, magnetic means for controlling the operation of the motive devices in either direction, circuits for said magnetic means including a control switch and two manual switches, said control switch in one 65 position in conjunction with both of said

manual switches completing circuits to cause the motive devices to open their doors, said control switch in another position completing circuits to cause one of said motive means to close its doors, and a third manual switch in 70 said circuit for completing circuits to cause the other of said motive devices to close its doors when said control switch is in normal position.

9. In a system for operating vehicle doors, 75 the combination comprising a motive device for each set of doors, one motive device being adjacent a control point and the other motive device being at a distance from the control point, magnetic means for operating the motive devices in either direction, a three position control switch at the control point, three manual switches at the control point and circuits including said magnetic means, control switch, and manual switches, said control switch in its first and normal position disconnecting the manual switches from said magnetic means, the control switch in its second position partially completing circuits to the magnetic means which are completed upon 80 closing two of the manual switches to cause the motive means to open the doors attached thereto, the control switch when moved to its third position completing circuits to cause the motive device adjacent the control point to 85 close its door, and the closing of the third manual switch completing circuits to the magnetic means to cause the doors remote from the control point to close their doors.

10. In a system of the type described for 90 controlling the doors on a number of vehicles comprising a train, the combination comprising motive devices for operating the doors on each of the vehicles, magnetic means for controlling the operation of the motive devices 95 in either direction, a control switch at a control point, three manual switches at the control point and circuits including the magnetic means, the control switch and the manual switches, the control switch being operable in 100 one position to partially complete the circuits to the magnetic means, one of said manual switches finally completing the circuits to the magnetic means of all the motive devices remote from the control point to cause 105 the doors to open, another of the manual switches being operable to complete the circuits to the magnetic means of the motive device adjacent the control point to cause the door thereat to open, the third manual switch being operable to complete circuits to the 110

magnetic means to cause all the motive devices remote from the control point to close the doors and the control switch being operable to another position to cause the motive device of the adjacent door to close its door.

11. In the combination of claim 10 a control switch on each of the cars for carrying out said operations from different control points.

12. In the combination of claim 10 control and manual switches on each of the cars for carrying out said operations at different control points.
- 5 13. In a system of the type described for operating the doors of vehicles, the combination comprising two motive devices, magnetic means for controlling the operation of the motive devices, circuits for said magnet means including a control switch at each end of the car and three manual switches at each end of the car, each of the control switches being operable to two positions, to one position to partially complete circuits to the magnetic means to cause both motive devices to open the doors when two of the manual switches at that end of the car are closed, and to the other position to cause one of the motive devices to close one of the doors, the third manual switch 10 at the same end of the car being actuatable to cause the other motive device to close its doors.
- 15 14. In a system of the type described, the combination comprising a series of electrically controlled door operating motive devices, means including a control switch operable to two positions from a normal position for controlling said motive devices, a plurality of manual switches and control circuits including all of said switches for controlling said electrically controlled motive devices, whereby said control switch is movable to one position to partially complete the control circuits, one of said manual switches being then 20 operable to cause all of the motive devices, except one, to operate in one direction, another of said manual switches being operable to cause the other motive device to operate in one direction, said control switch being operable to another position to cause all of the motive devices but the excepted one to operate in the opposite direction, and said excepted motor being operable in the opposite direction by another of the manual 25 switches when the control switch is in normal position.

In testimony whereof I have hereunto set my hand on this 13th day of January, A. D. 1931.
